UNITED STATES PATENT OFFICE

FREDERICK H. WILDE, OF CHICAGO, ILLINOIS, ASSIGNOR TO GUY S. FABER

AIR CONDITIONING APPARATUS

Application filed August 23, 1930. Serial No. 477,875.

My invention relates more particularly to apparatus for the cleaning of air and the changing of the moisture content and temperature thereof as desired, the invention 5 having been devised for use more particularly in connection with the supplying of air to rooms of a building.

One of my objects is to provide novel, simple and relatively inexpensive apparatus 10 for the general purpose above stated.

Another object is to provide apparatus of the general character above referred to which will operate with greater efficiency than structures as hitherto provided.

15 Another object is to provide an apparatus which may be utilized during warm weather to cool, and preferably to remove excess moisture from, the air before supplying it to the rooms and may be utilized in cold weather to 20 heat and humidify the air prior to supplying it to the rooms.

Another object is to provide in an apparatus employing a power-operated air-forcing device, such as an electric fan, for the 25 relatively free circulation of the air through the conditioning apparatus with the minimum likelihood of undesirable leakage of water, and the entraining of the moisture 30 in such finely divided condition as not to produce objectionable collection of drops of water on objects in the room; and other objects as will be manifest from the following description.

35 Referring to the accompanying drawings: Figure 1 is a face view of the wall structure which may be a side wall of the room of a building, of a cabinet, equipped with air-conditioning apparatus in accordance with one of the embodiments of my invention.

40 Figure 2 is a view in sectional elevation of the structure shown in Fig. 1, the section being taken to the rear of the front wall shown in Fig. 1, the section line being indicated at 2-2 on Fig. 3 the direction in which the figure is viewed being indicated by the arrows.

45 Figure 3 is a section taken at the line 3 on Fig. 1 and viewed in the direction of the 50 arrow.

Figure 4 is a plan sectional view taken at the line 4 on Fig. 2 and viewed in the direction of the arrow.

Figure 5 is a broken vertical sectional view in elevation, taken at the irregular line 55 5-5 on Fig. 3 and viewed in the direction of the arrow.

Figure 6 is an enlarged sectional view taken at the line 6 on Fig. 2 and viewed in the direction of the arrow.

60 Figure 7 is a view like Fig. 3 of a modification of the apparatus therein shown, the section being taken at the line 7-7 on Fig. 8 and viewed in the direction of the arrows.

Figure 8 is a vertical sectional view taken 65 at the irregular line 8-8 on Fig. 7 and viewed in the direction of the arrows.

Figure 9 is a broken view in sectional elevation of a portion of the structure shown in Fig. 7 illustrating a modification thereof.

70 Figure 10 is a view in vertical sectional elevation of another embodiment of my invention.

Figure 11 is a broken view, partly sectional, of a portable air conditioner embodying my invention, the section being taken at the line 11 on Fig. 12 and viewed in the direction of the arrow; and

75 Figure 12, a section taken at the line 12 on Fig. 11 and viewed in the direction of the arrow.

Referring to the apparatus illustrated in Figs. 1 to 6, inclusive, 13 and 14 represent spaced apart wall-forming sections of a building, or of a cabinet, the wall-section 13 being located at the inside of the space to receive the air conditioned by my invention and containing a lower opening 15 therethrough which would be located above the floor of said space, as for example about 80 three feet above the floor, and an upper opening 16.

85 The lower opening 15 is provided with a grid-like door 17 shown as hinged at 18 to a frame 19 positioned in the opening 15 and the upper opening 16 is provided with a grid-like plate 20 in the form of a register.

90 Located in the space between the walls 13 and 14 is a sheet metal casing 21 forming a conduit, its upper end, which is open, being 100

of elbow form and fitting into the opening 16 and thus in registration with the register 20, the conduit 21 containing, adjacent the register 20, a vertical series of substantially horizontally-disposed vertically-spaced eliminating plates 22 for intercepting entrained large drops of water should such be carried up with the air.

The lower portion of the rear wall of the conduit 21 is forwardly curved as represented at 23, its front edge terminating in a substantially vertically extending portion 24, the portions 23 and 24 being of substantially the same width as the conduit 21 and forming a trough through the bottom of which a drain pipe 25 opens.

The front wall of the conduit 21 is shown as formed of two sections 25 and 26, the section 25 being of the full width of the conduit 21. The section 21 terminates at its lower edge adjacent the upper edge of the opening 15 and is deflected rearwardly as represented at 27 to afford a rearwardly offset flange. The section 26, forming a continuation of the section 25, is hinged thereto as represented at 28 and is downwardly and rearwardly curved as shown terminating at its rear portion in an upwardly-extending lip-portion 29. The section 26, which thus forms a trough, is preferably spaced at its ends a slight distance from the sides of the conduit 21 as shown in Fig. 5 when it extends horizontally as shown. The trough 26, however, may be inclined from one end to the other in which case it need not be spaced at both ends from the conduit.

Mounted on the door 17, by a bracket 17^a, is an air forcing device shown as in the form of an electric motor 30, the armature shaft 40 of which carries a fan propeller 31, the axis of the fan being shown as extending slightly below the lowermost portion of the trough 26. The fan serves to draw air through the opening 15 in the wall 13 and force it into the lower end of the conduit 21 through which the air upwardly flows discharging through the register 20 into the room.

Mounted on brackets 32 and 33 in the conduit 21 is a vertically disposed pipe-coil 34 comprising substantially horizontally disposed pipe portions 35 arranged in staggered position in a vertical series, the ends of the pipe sections 35 being connected together by cross pipes 36 disposed alternately at opposite sides of the pipe coil 34.

In the construction shown the mounting of the pipe coil 34 on the brackets 32 and 33 is at the lower and upper ones, respectively, of the horizontal pipes 35.

The pipes 35 are each provided with a horizontal series of spaced apart disk-like members 37 which form radiating fins.

Each of the alternate ones of the horizontal pipes 35 supports a trough 38 which extends crosswise of the conduit 21, these troughs

being connected with the pipes 35 as by soldering them thereto, portions of the fins 37 on the pipes 35 equipped with the troughs 38 being cut away as represented so that they will conform at their edges with the undersides of the troughs and preferably be in thermal-conducting relation thereto, being soldered to the troughs if desired.

The troughs 38, shown as connected with alternate ones of the pipes 35, are disposed in a general upright series but preferably are arranged in staggered relation as represented in Fig. 3, each successive one of these troughs being of less width than the one below it as shown in Fig. 2 so that the water supplied to these troughs, as hereinafter described and discharging from the ends thereof, will fall from one to the other of the troughs of the series thereof. In other words, the water will cascade from the uppermost trough to the one next below it and from the last referred-to trough to the third from the top and from the latter to the lowermost trough.

The troughs 38 are closed at their opposite ends as indicated at 39 whereby the cascading referred to results from the overflowing of the water from these troughs.

Extending across the series of troughs 38 at their forward edges to span the vertical spaces therebetween, and of a width equal to the length of the troughs 38 is a member 40 of wire mesh which is in contact with the front edges of the trough and which is supplied with water overflowing the troughs 38 at their front edges, the member 40 being in contact with the fins on the forwardmost ones of the pipe sections 35 and preferably soldered thereto.

The pipe coil 34 is connected at its upper end with a pipe 41 which leads from any suitable source of heating medium, as for example, steam under pressure, when the apparatus is to be used during cold weather for the heating and humidifying of the air discharging through the register 20, and leads from a source of cooling medium, such as cold water or refrigerating fluid, when the apparatus is to be used in warm weather for cooling, or cooling and dehydrating, the air supplied through the register 20, the lower end of the coil 34 connecting with a pipe 42 through which the steam, or water, as the case may be, discharges from the coil 34.

Located in the conduit 21 is an upwardly extending pipe 43 terminating at its upper end in horizontally spaced branch outlets 44 located directly above the uppermost ones of the troughs 38 adjacent the opposite ends of the latter, the pipe 43 being provided for the purpose of conducting into the uppermost trough 38 for flow therefrom successively into the troughs 38 below it and for flow downwardly over the member 40, hot water in the use of the apparatus during cold weather and cold water during warm

weather. The lower end of the pipe 43 opens into a passage 44 in a valve casing 45 provided with a needle valve 46 which controls the flow through the passage 44, the passage 44 leading from a strainer device 47 having a chamber 48 divided by a screen partition 49. The passage 44 opens into the chamber 48 on one side of the screen 49, and the chamber 48 at the other side of the screen opens 10 into a passage 50 in the valve casing 45 which connects with a pipe 51 which would lead to a source of hot water or cold water, as the case may be. The stem of valve 46 extends outwardly through one of the opposing grid 15 members 17 as shown to permit of the manipulation of this valve from a point exterior of the member 17.

The wall section 26 of the conduit 21 is shown as releasably held in the position illustrated in Fig. 3 in which it serves to receive such of the water as may overflow from the lowermost trough 38 and drops from the lower edge of the screen member 40, the water thus flowing in the trough 29 flowing 25 along this trough to its lower end where it discharges at the side of the conduit 21 into the trough formed of the portions 23 and 24 of the conduit 21 and thence flows out through the pipe 25.

30 As will be understood from the foregoing description, the flow of air into the lower end of the conduit 21 and produced by the fan 31 moves crosswise of and beneath the trough 26 thence rises in the conduit 21 in which it spreads out and is subjected to the heat of the coil 34 and of the hot water in the troughs 38 and on the screen member 40, in the use of the apparatus in cold weather; and to the cooling effect of the coils and the cooling 35 medium supplied to the members 38 and 40 in the use of the apparatus in hot weather. The provision of the trough member 36 insures the travel of the air out of contact with the water discharging from the lowermost 40 trough 38 and the member 40, resulting in avoiding the carrying up in the air currents of water in relatively objectionable, large, particles.

The motor 30 being carried by the swinging door 17, and the trough portion 26 being movable forwardly, by swinging it at its hinge connection 28 with the conduit wall-section 25, the parts of the apparatus which would otherwise be covered up are rendered 55 accessible for cleaning or repair, the trough 26 being shown as normally held in trough-forming position by a spring clip 52 secured to the rear wall of the conduit 21 and having a latch portion 53 at which it interlocks 60 with a lug 54 on the trough section 26.

Referring to the construction shown in Figs. 7 and 8, this construction embodies the conduit which opens at its top and bottom into the room, the air-forcing device, the 65 lower trough section forming a continuation

of the rear wall of the conduit and the second trough section disposed above the first-referred-to section and serving to direct the air currents produced by the fan, toward the rear wall of the conduit and to direct 70 water in the trough along the latter for end discharge therefrom all as shown in the construction of the preceding figures, and therefore the same designating numerals have been applied thereto. 75

This construction differs from the one of the preceding figures in that, instead of providing the humidifying or cooling means for the air as shown in this preceding construction, means are provided for directing upwardly in the conduit sprays of either heated or cool water, depending on whether the apparatus is to be used in the winter or summer. The spraying means shown comprise a pipe 55 located in the conduit directly above, and in close proximity to, the trough 26, this pipe being provided at its ends with spray nozzles 56 preferably diverging upwardly as shown for spraying upwardly in the conduit intersecting spray streams of water which impinge against all sides of the conduit 21. The pipe 55 is connected between its ends with a pipe 57 which corresponds with the pipe 43 and leads from a water strainer in communication with a water supply pipe represented at 58, as in the case of the construction of the preceding figures, the flow of water from the pipe 58 to the pipe 57 being controlled by a valve as in the case of the preceding construction. 90

It will be understood from the foregoing that the air forced upwardly through the conduit 21 by the action of the fan 31 contacts with the sprayed water issuing from the nozzles 56 resulting in the heating, cleansing and humidifying of the air when the water is supplied in heated condition and in the cleansing and cooling of the air when the water is supplied in cool condition, it being observed that by directing the water spray upwardly in the conduit and thus in the direction of the natural flow of heated air in the conduit the air is subjected to the action of the water much more effectively than in the case where the water is sprayed in the reverse direction only and the possibility of relatively large particles of water becoming entrained with the air and discharging into the room, is greatly minimized. 100

It will be noted that in the spraying of the water as stated, the air is not only subjected to the rising spray but also to a descending spray comprising such of the water as does not become entrained, in its upward movement, in the air whereby the apparatus is rendered not only very effective but economical 115 in operation.

Such of the water as does not become entrained in the air flows into the troughs 26 and 23, the water flowing from the latter 130

endwise thereof into the trough 23 and thence through the drain outlet.

If desired, the trough section 26 instead of being hinged to the casing section 25 may be connected with, and supported by, the door 17, whereby this trough, by the single act of opening the door 17, may be swung out of operative position to permit of access to the parts of the apparatus which would otherwise be obstructed thereby. Such arrangement is shown in Fig. 9 wherein it will be noted that the trough 26 is connected with the door 17 by a bracket member 59 and thus swings therewith.

15 Referring to Fig. 10 of the drawings, the construction therein shown is provided as an apparatus intended for location in a portion of a building remote from the room, or rooms, to be supplied with heated and humidified 20 air, or cool air, as the case may be, as for example in the basement of a building.

The apparatus shown comprises a casing 60 for supplying conditioned air to a room 61 of a building located thereabove. The 25 casing 60 is provided in its top wall with an opening communicating with the lower end of a pipe 62 which opens at its upper, preferably register-equipped, end through an opening in the floor 63 of the room 61, the 30 top of the casing 60 containing another opening represented at 64 through which the lower, elbow-shaped, end 65 of a pipe 66 extends, the upper end of this pipe opening into the room 61 through an opening 67 in a wall 68 35 of the room. The pipe 62 serves to conduct air from the room 61 into the casing 60 where it is conditioned, as hereinafter described, and the pipe 66 serves to convey the conditioned air for discharge into the room 61.

40 The casing 60 contains a hopper-shaped casing 69 open at its upper end, at which it is preferably equipped with an air filter represented generally at 70, as for example in the form of a single sheet of filtering paper

45 or a mass of mineral wool, as is commonly used, the upper end of the casing 69 being thus in communication with the pipe 62. The lower end of the casing 69 opens into the inlet end of a blower 71 located in the 50 bottom of the casing 60, the discharge end of this blower opening into the funnel-shaped inlet 72 of a conduit 73 also located in the casing 60 and connected at its upper, outlet, end 74 with the inlet end 65 of the pipe 66.

55 The lower portion of the conduit 73 is shaped to form a sump 75 from which leads a drain pipe 76 and the rear wall of the conduit at the portion thereof against which the main portion of the blast from the blower 71 impinges, curves rearwardly and upwardly as represented at 77, the conduit 73 at the portion 77 thereof being provided with a coil 78 for circulation therethrough of a heating or cooling medium, as desired.

60 Located between the upper and lower ends of the conduit 73 is a trough 79 extending

crosswise of the conduit 73 and related at its ends thereto as explained of the trough 26 of the preceding figures of the drawings, this trough being so disposed, as shown, that the air delivered by the blower 71 impinges 70 against its curved undersurface and is thus deflected and guided thereby toward the rear side of the conduit 73.

65 Located directly above the trough 79 are means for upwardly spraying water either 75 heated or cool, into the conduit 73 into a position in which it is contacted by the air flowing upwardly through the conduit 73. The means shown comprise one or more spray nozzles 80 (a plurality thereof being preferably provided and disposed as in the case of the nozzles 56 in Figs. 7 and 8), the nozzle, or nozzles, as the case may be, being connected with a pipe 81 which would lead to any suitable source of water under pressure. The spray means are preferably provided with valve means, such as that represented at 82, for controllably regulating the flow of water from the pipe 81 to the nozzle, or nozzles, 80, the nozzle structure being preferably provided with valve means, the stem of which is represented at 83 for controlling the character of the spray and the spread of the stream of spray as is common in spray-nozzle constructions.

70 Eliminator plates shown as arranged in parallelism and located adjacent the outlet 74 of the conduit 73, are also provided to function as in the case of the plates 22 of Fig. 3. These eliminator plates, represented at 84, are shown as pivotally supported at 85 on the wall of the conduit 73, with their upper ends connected together by a link 86 pivoted thereto. An arm 87 is connected with one of the pivots 85 and pivotally connects at 88 with the inner end of a slide rod 89 extending through the casing 60 to be accessible for operation from the exterior of the casing.

75 It will be understood from the foregoing that the air in flowing upwardly in the conduit 73 is subjected to the cooling, or heating, effect, as the case may be, of the coil 78 and thence passes upwardly through the water spray which removes dirt from the air humidifying and heating it in the case of hot water being supplied to the coil 78, and cooling it in the case of the use of a cooling medium therein, the air thus conditioned discharging through the pipe 66 into the room 61, the trough 79 functioning as in the case of the 120 trough 26 of the preceding figures and as above described therein, such of the water discharged from the water-spraying means as does not become entrained in the air flowing in the conduit 73, flowing into either the trough 79 or sump 75, the water which flows into the trough 79 discharging therefrom into the sump.

80 Preferably means are provided for preventing water which may collect on the rear 130

wall of the conduit 73 from flowing down onto the coil 78, such means, in the construction shown, being provided by forwardly deflecting the rear wall of the conduit above the coil 78 as represented at 73^a to cause such deflected portion to extend forwardly of the lower end of the coil, whereby water dripping from the lower edge of the conduit wall portion 73^a drops clear of the coil.

10 The construction shown in Figs. 11 and 12 is designed primarily as a unit to be shifted from one location to another, as for example from one room to another as in the case of a hospital, where it is desired to supply a room, 15 or rooms, with cleansed air, in some cases humidified and heated, and in other cases cooled.

20 This construction as shown comprises a casing 90 mounted on casters 91 permitting it to be rolled from one location to another as desired.

25 Mounted in the lower portion of the casing 90 is a blower 92 shown as operated by an electric motor 93. The blower shown is of the centrifugal type containing inlets at its opposite sides which open into the casing 90, the latter being provided at its lower portion with inlets 94 for the air to be conditioned, the inlets being preferably screened as represented at 95 as for example by relatively 30 fine wire mesh.

35 The outlet 96 of the blower is connected with a pipe 97 which opens at its upper, elbow, portion 98 through an opening 99 in an upwardly extending conduit 100 located in the casing 90, the upper end of this conduit, which is in the form of an elbow as represented at 101, communicating with an outlet opening 102 in one of the side walls of the casing 90 for discharge from the casing of the air 40 conditioned as hereinafter explained, the outlet of this conduit being preferably screened, as by fine wire mesh represented at 103. The upper end of the conduit 100 preferably is equipped with eliminator plates represented 45 at 104 constructed and regulated as explained of the plates 84 in the construction shown in Fig. 10.

50 The casing 100 contains an upwardly and rearwardly curved deflector plate 105 extending crosswise thereof and opposite the outlet end of the pipe 97 against which the air discharged through this pipe by the blower 92 impinges thereby being deflected upwardly.

55 Located above the deflector plate 105 is a trough 106 connected with the front wall of the conduit 100, the ends of the trough 106 being related to the adjacent sides of the conduit 100 as explained of the construction of the preceding figures of the drawings. The trough 106 is spaced at its rear edge from the upper end of the conduit 105 thereby 60 providing an air passage between these parts.

65 Located directly above the trough 106 are means, represented generally at 107, for upwardly spraying water either heated or cool,

as conditions require, the construction of which may be the same as that described of the structure shown in Fig. 10. The pipe for supplying water to the spraying means 107 is represented at 108 and is shown as connected with the outlet of a pump 109 shown as operated by the shaft of the motor 93, the inlet 110 of the pump 109 being connected with a pipe 111 which opens into the closed bottom portion of the conduit 100.

70 The apparatus now being described operates substantially the same as that disclosed in Fig. 10, such of the water as does not become entrained in the air flowing in the conduit 100, gravitating into the lower portion of the conduit 100 from which it flows into the pump 109 and is returned to the spray means 107, the lower closed portion of the conduit 100 forming a receptacle for water the supply of which therein may be replenished from time to time as the supply thereof becomes diminished by its entrainment in the air and discharging from the casing 90.

75 Preferably the apparatus also comprises a heater device represented at 112 disposed in the line of flow of the air to the inlet of the blower for heating the air, this device in the construction shown being represented diagrammatically as an electric heater.

80 While I have illustrated and described my invention as embodied in certain forms of construction, I do not wish to be understood as intending to limit it thereto as the same may be variously modified and altered and the invention incorporated in other forms of 85 structure without departing from the spirit of my invention.

85 What I claim as new, and desire to secure by Letters Patent, is:

1. Air conditioning apparatus comprising 90 a conduit for the flow therethrough of the air to be conditioned, air conditioning means for subjecting air to water in said conduit, and an end-discharging water-receiving trough at the lower portion of said conduit crosswise along the underside of which the air to be conditioned flows, the apparatus having a lower air inlet and an upper air outlet.

105 2. Air conditioning apparatus comprising a conduit for the flow therethrough of the air to be conditioned, and air conditioning means for subjecting the air to water in said conduit, opposed walls of said conduit at their lower ends having portions extending inwardly toward each other and disposed one above the other in vertically spaced relation and providing a passage therebetween for the air to be conditioned, the uppermost one of said portions being in the form of an imperforate

110 trough, the apparatus having a lower inlet 115 for air in registration with said passage and an upper outlet for the conditioned air.

120 3. Air conditioning apparatus comprising a conduit for the flow therethrough of the air

to be conditioned, air conditioning means for subjecting the air to water in said conduit, a water receiving trough at the lower portion of said conduit, and air forcing means comprising an electric motor, positioned to direct its discharge crosswise along the underside of said trough for upward flow in said conduit, said trough shielding said motor from contact with the water dropping in said conduit.

4. Air conditioning apparatus comprising a conduit for the flow therethrough of the air to be conditioned, air conditioning means for subjecting air to water in said conduit, an end-discharging water-receiving trough at the lower portion of said conduit crosswise along the underside of which the air to be conditioned flows, and a trough below said first-named trough for receiving the discharge from the latter, the apparatus having an inlet at the lower end for air and an upper outlet for the conditioned air.

5. Air conditioning apparatus comprising a conduit for the flow therethrough of the air to be conditioned, air conditioning means for subjecting the air to water in said conduit, an end discharging water receiving trough at the lower portion of said conduit, an air-deflecting trough below said first-named trough for receiving the discharge from the latter and vertically spaced therefrom, and air forcing means positioned to direct its discharge crosswise along the underside of said first-named trough, the inner edge of said second-named trough extending in the opposite direction to flow of air.

6. Air conditioning apparatus comprising a conduit for the flow therethrough of the air to be conditioned, and having a lower inlet and an upper outlet, a door for said inlet, air conditioning means for subjecting the air to water in said conduit, an end discharging water receiving trough at the lower portion of said conduit and air forcing means mounted to move with said door and positioned to direct its discharge crosswise along the underside of said trough.

7. Air conditioning apparatus comprising a conduit for the flow therethrough of the air to be conditioned, air conditioning means for subjecting air to water in said conduit, and an end-discharging water-receiving trough at the lower portion of said conduit crosswise along the underside of which the air to be conditioned flows, said trough being adapted to be shifted out of operative position for permitting access to the interior of said conduit.

8. Air conditioning apparatus comprising a conduit for the flow therethrough of the air to be conditioned, air conditioning means for subjecting air to water in said conduit, and an end-discharging water-receiving trough at the lower portion of said conduit crosswise along the underside of which the

air to be conditioned flows, said trough being pivotally supported to adapt it to be shifted out of operative position for permitting access to the interior of said conduit.

9. Air conditioning apparatus comprising a conduit for the flow therethrough of the air to be conditioned, air conditioning means for subjecting air to water in said conduit, and an end-discharging water-receiving trough at the lower portion of said conduit crosswise along the underside of which the air to be conditioned flows, said trough being pivotally supported on the front wall of said conduit to adapt it to be shifted out of operative position for permitting access to the interior of said conduit.

10. Air conditioning apparatus comprising a conduit for the flow therethrough of the air to be conditioned and having a lower inlet and an upper outlet, a door for said inlet, air conditioning means for subjecting the air to water in said conduit, an end-discharging water-receiving trough at the lower portion of said conduit and carried by said door, and air forcing means mounted to move with said door and positioned to direct its discharge crosswise along the underside of said trough.

11. Air conditioning apparatus comprising a conduit for the flow therethrough of the air to be conditioned and having a lower inlet and an upper outlet, a screen extending upwardly in said conduit, a trough in said conduit, means for supplying water to said trough, said trough overflowing upon said screen, and a coil in said conduit for a temperature changing medium extending along said screen.

12. Air conditioning apparatus comprising a conduit for the flow therethrough of the air to be conditioned and having a lower inlet and an upper outlet, a screen extending upwardly in said conduit and upwardly extending series of troughs in said conduit and means for supplying water to said series of troughs, said troughs overflowing upon said screen.

13. Air conditioning apparatus comprising a conduit for the flow therethrough of the air to be conditioned and having a lower inlet and an upper outlet, an upwardly extending series of troughs in said conduit of progressively greater length from the upper to the lower portion of said series, whereby water supplied to the troughs overflows in succession from the ends thereof to the troughs below, and means for supplying water to said troughs.

14. Air conditioning apparatus comprising a conduit for the flow therethrough of the air to be conditioned and having a lower inlet and an upper outlet, a screen extending upwardly in said conduit and upwardly extending series of troughs in said conduit and means for supplying water to said series of troughs, said troughs overflowing

upon said screen and from one to the other of said troughs in succession.

15. Air conditioning means comprising a casing having an inlet in its lower end for the air to be conditioned and an outlet in a side wall adjacent its upper end for the conditioned air, means for contacting the air in its passage from said inlet to said outlet to water, said casing being formed with a deflector plate for deflecting the conditioned air toward said outlet, and water-eliminating means between said outlet and said first-named means.

16. Air conditioning means comprising a casing having an inlet in a side wall thereof at its lower end for the air to be conditioned and an outlet in a side wall thereof adjacent its upper end for the conditioned air, means for conducting the air in its passage from said inlet to said outlet to water, an upwardly and rearwardly curved deflector plate at the lower end of said casing extending at its lower end toward said inlet and along which the air upon entering said casing flows and is deflected upwardly, and a curved deflector plate at the upper end of said casing for deflecting the air toward said outlet, said means being located between said deflector plates.

30 17. Air conditioning means comprising a casing having an inlet in a side wall thereof at its lower end for the air to be conditioned and an outlet in a side wall thereof adjacent its upper end for the conditioned air, means for conducting the air in its passage from said inlet to said outlet to water, an upwardly and rearwardly curved deflector plate at the lower end of said casing extending at its lower end toward said inlet and along which the air upon entering said casing flows and is deflected upwardly, a curved deflector plate at the upper end of said casing for deflecting the air toward said outlet, said means being located between said deflector plates, and water eliminating means between said outlet and said first-named means.

18. Air conditioning apparatus comprising a conduit for the flow therethrough of the air to be conditioned, means for causing water in finely divided condition to be subjected to air flowing upwardly in said conduit, a trough at the lower portion of said conduit to intercept the water flowing in said conduit and crosswise along the underside of which the air to be conditioned flows, the conduit having a lower air inlet and an upper air outlet.

FREDERICK H. WILDE.
